CLAIM

The ornamental design for a luminous hockey ball as shown and described.

DESCRIPTION

FIG. 1 is a front, right and top perspective view of a luminous hockey ball, showing my new design;
FIG. 2 is a rear, left and bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a cross-sectional view thereof taken along section line 9-9 of FIG. 3;
FIG. 10 is an exploded, front, left and top perspective view thereof; and,
FIG. 11 is an exploded, right, top perspective view thereof. The dashed broken lines depict portions of the luminous hockey ball that form no part of the claimed design.
